DYNAMOELECTRIC MACHINE

Stanley E. Tomkinson, Fort Wayne, Ind., assignor to
General Electric Company, a corporation of New
York

Filed May 14, 1969, Ser. No. 17,151

Term of patent 14 years

Int. Cl. D13—01

U.S. Cl. D26—5

FIG. 1

FIG. 2

FIG. 3

FIG. 4

FIG. 5

FIG. 1 is a top plan view of a dynamoelectric machine showing my new design;

FIG. 2 is a side elevational view of the dynamoelectric machine as seen from the top in FIG. 1;

FIG. 3 is a side elevational view of the dynamoelectric machine as seen from the bottom in FIG. 1;

FIG. 4 is an end elevational view as seen from the right in FIG. 1; and

FIG. 5 is an end elevational view as seen from the left in FIG. 1.

I claim:

The ornamental design for a dynamoelectric machine, as substantially shown and described.
